UNITED STATES PATENT OFFICE.

DAVID WELLS, OF LOWELL, MASSACHUSETTS.

STOVE.

Specification of Letters Patent No. 22,392, dated December 21, 1858.

To all whom it may concern:

Be it known that I, DAVID WELLS, of Lowell, in the county of Middlesex and State of Massachusetts, have invented a new and useful Improvement in Smoke-Consuming Stoves, Furnaces, &c.; and I do hereby declare that the following is a full, clear, and exact description of the same, reference being had to the annexed drawings, 10 making a part of this specification, in which—

Figure 1, is a transverse vertical and central section of a stove with my improvement applied to it. Fig. 2, is a longitudinal 15 vertical section of ditto, taken in the line x, x , Fig. 1. Fig. 3, is a horizontal section of ditto, taken in the line y, y , Fig. 1.

Several letters of reference indicate corresponding parts in the several figures.

20 This invention consists in a peculiar arrangement of flues, an air-heating chamber and smoke chamber substantially as herein-after fully shown and described, whereby the combustible portion of the products of 25 combustion is brought in contact with a suitable portion of heated atmospheric air and ignited in a chamber separate from the fire chamber, but by the heat or fire therefrom.

30 The object of the invention is to obtain all the advantages derived from the consuming of the combustible portion of the products of combustion without detracting from the efficacy of the fire chamber itself 35 as a source of heat, by admitting directly upon or over the fire atmospheric air in order to consume the inflammable portion of the escaping gases.

To enable those skilled in the art to fully 40 understand and construct my invention I will proceed to describe it.

A, represents the body of a stove which may be of rectangular or any suitable form and B, is the fire chamber at the lower part 45 of the stove.

C, is the ash pit below the grate D, of the fire chamber.

D', D', are two flues, placed one at each side of the stove at its back part. These 50 flues extend down a certain distance and communicate with a chamber E, which at its upper part extends the whole width of the stove and extends down to the bottom of the stove and communicates with the smoke pipe F. Between the chamber E, and the

55 back plate a, of the stove there is a chamber G, which communicates with the external air by means of passages b, b, which ex-

tend down through the chamber E, one at each side see dotted lines in Figs. 2 and 3. 60 The chamber G, communicates with the chamber E, by means of perforations a, and the chamber E, communicates with the fire chamber B, by means of perforations b.

The operation is as follows:—When the 65 fire is kindled in B, the smoke and products of combustion will pass upward in the body A, of the stove and then down the flues D', into the chamber E. Cold air passes up 70 through the passages b, b, into the chamber G, and becomes heated. This heated air passes through the perforations a, see blue arrows, and mixes with the products of combustion in the chamber E, and a small quantity of flame from the fire chamber B, will 75 pass through the perforations b, into the chamber E, and ignite the inflammable product in E, which consequently is a supplemental heating chamber. It will be understood that the draft upward in the body A, 80 of the stove and down the flues D', is sufficiently strong to carry with it all the smoke and inflammable gases, a small portion of flame only, will pass through the perforations b, just sufficient to ignite the products 85 of combustion in E, as soon as it mixes with heated atmospheric air. By this arrangement it will be seen that the fire in the chamber B, will not be cooled or deadened 90 by the admission of the external air directly upon it, and that the supplemental smoke consuming device is an auxiliary affair and can not detract in any way from the efficiency of the fire chamber B.

I am aware that various plans have been 95 devised for admitting heated air into stoves and furnaces, so that the products of combustion may be mixed therewith in order to insure the burning of the same. I therefore do not claim broadly such idea, but 100

Having thus described my invention, what I claim as new and desire to secure by Letters Patent, is—

The arrangement of the flues D', D', smoke chamber E, air heating chamber G, 105 and fire chamber B, the latter communicating with the smoke chamber by means of perforations b, and the smoke chamber communicating with the air heating chamber by perforations a, substantially as and for the 110 purpose set forth.

DAVID WELLS.
